UNITED STATES PATENT OFFICE

2,476,488

LIPSTICK CASE

Sophie Frydlender, Paris, France, assignor to
 Lancome Societe Anonyme, Courbevoie, France,
 a corporation of France

Application May 15, 1945, Serial No. 593,804
 In France October 29, 1943

Section 1, Public Law 690, August 8, 1946
 Patent expires October 29, 1963

12 Claims. (Cl. 206—56)

1

The present invention relates to a lip-stick case remarkable owing to its robustness, its modern and original appearance and the ease with which it can be handled even with gloves. The user's fingers are not liable to come into contact with the lip-stick owing to their distance from the latter. Since no piece is removable, there is no risk of any of them getting lost. Finally, the case cannot open accidentally; it offers a completely closed appearance; and comprises no knob or slot liable to get caught in the hand-bag.

The lip-stick case according to the invention is more particularly characterized by the fact that it comprises an external cover containing a shifting tube fast with the base of the case and in which the lip-stick holder or socket is located, the shifting tube carrying a projection which co-acts with a guiding device located inside the cover of the case so as to allow the tube to slide longitudinally downwardly while carrying along a flap closing the case, and then to be shifted angularly when it has reached the end of its downward stroke in order that it may be set free from the closing flap and made fast with the stick-holder socket. Thereafter the shifting tube is moved upwardly in the case to project the lip-stick held by the stick-holder socket out of the case in position for use. Retraction of the lip-stick and returning of the flap to closed position are accomplished by operations in the reversed sense.

An object of the invention is to provide a lip-stick case having the constructional features and operating characteristics and advantages referred to.

A lip-stick case embodying the invention possesses numerous other characteristic features which will appear from the following description of a form of execution shown by way of non-limitative example in the appended drawings.

In said drawings:

Figure 1 is a perspective view of the closed case.

Figure 2 is a perspective view of one of the elements of the inner guiding device located in the case.

Figure 3 is a top perspective view and Figure 4 is an underneath perspective view of a piece forming a guiding bridge co-acting with the element of Figure 2.

Figure 5 is a perspective view of the shifting tube.

Figures 6 and 7 are perspective views of the flap closing the case and of organs connected with this flap.

2

Figures 8, 9, and 10 are three perspective views making clear the handling of the case.

Figure 11 is a diagrammatic cross sectional view hereinafter referred to in explaining the working of the device.

Figure 12 is a fragmentary longitudinal section showing a buffer on the shifting tube.

Figure 13 is a fragmentary elevation showing the buffer as viewed from the left of Figure 12.

Figure 14 is a transverse section on the line 14—14 of Figure 13.

Figure 15 is a fragmentary longitudinal section showing a slot in the shifting tube.

Figure 16 is a fragmentary elevation showing the aforesaid slot as viewed from the left of Figure 15.

Figures 17 and 18 are diagrammatic views showing respectively relative positions of certain of the parts when the flap is closed and opened.

Figures 19, 20, and 21 are phantom or exploded perspective views respectively showing the positions occupied by the parts during successive stages of operation.

The case comprises a cover 1 (Figure 1) in which is located a guiding element 2 (Figure 2) which will hereafter be called a slide and on which is mounted a guiding bridge 3 (Figures 3 and 4). In the slide 2 is located a shifting tube 4 provided with a base 5 (Figure 5) and containing the stick-holder socket 6 in which the lip-stick is fitted. A flap 7 (Figures 6 and 7) provides for the closing of the cover.

The cover 1 includes a rectangular face 8, a half cylindrical face 9 and two parallel parts 10 connecting the half cylindrical part 9 with the side edges of face 8. The rectangular face 8 terminates in an upper part 11 having the shape of a quarter of a cylinder, the generatrix 11' of which is perpendicular to both side faces 10. A circular opening 12 in part 11 provides a passage for the lip-stick when pushed out.

The slide 2, which lies inside the said cover and which is shown in Figure 2, fits a large part of the inner surface of cover 1. Between the upper edge 13 of the slide 2 and the corresponding part 11 of the cover 1 is provided a play approximately equal to the thickness of the closing flap 7 (shown in Figures 6 and 7) to make it possible for the latter to slide. The edge 13 of the slide 2 carries a small projection 14 which strikes against the inner part of the cover 1 and determines the thickness of this play. The slide 2 has substantially the form of a curved stirrup including two legs 15, 16 notched at 15', 16' for receiving the guiding bridge 3, shown in Figures

3 and 4. The leg 16 is folded up inwardly in order to form a flange 17 substantially fitting the cylindrical surface of the shifting tube 4 shown in Figure 5. About its middle part, the flange 17 is provided with a small sloping surface 18 insuring the automatic release of the closing flap 7 when the latter has reached the end of its stroke, as will be explained hereafter. The upper end of the flange 17 is separated from the leg 16 by a small slot 19 in order to form an elastic lug 20 stamped in the shape of a V and fitting into a notch 21 of the shifting tube 4 for releasably locking the parts in the closed positions shown in Figures 1 and 19.

The guide-bridge 3 shown in Figures 3 and 4 is a T-section piece, the flanges of which rest on the edges 15', 16' of the slide. One of the flanges which rests on the edge 16' is provided with a bent portion 22. The vertical plane formed by the web of the T and designated by 23 serves as a guide for a buffer 24 formed on the shifting tube 4, the buffer running along the left side of the web while running downwardly and along its right side while running upwardly to push out the stick, as will be explained later on. A notch is provided at 25 for the passage of the buffer 24 from the left to the right and conversely. The upper right flange of the bridge 3 is extended and folded up at 26 and is formed with a small groove 27 which retains a pin 28 on the stick-holder at the bottom 5' of the case 1 when it is desired to close the latter again. A clearance 29 is also provided for the passage of the pin 28 longitudinally away from the small groove 27.

The shifting tube 4 (Figure 5), fast with the base 5, is provided with a longitudinal groove 30 terminating at its upper end in a right angle part 31 extending from the right to the left. Below this part lies the buffer 24 which, as viewed from the outside and diametrically of the tube 4, is of V or inverted V shape, and thus is rigid with respect to the tube 4. The buffer 24 may be formed of two flaps 24^a and 24^b bent outwardly to meet each other as shown in Figure 13, thus forming the V. During the shifting, the buffer 24 strikes through its lower part against the bottom 5' of the case, and prevents the tube 4 from moving completely out of the cover 1. The upper edge of the square hole formed through cutting out the buffer is pressed slightly outwardly so as to form a projection of the cylindrical part along a slightly sloping plane 32. Near the top of the shifting tube 4 the notch 21 receives the elastic lug 20 which acts to lock the tube 4 in closed position.

The shifting tube 4 contains the socket 6 in which the lip-stick is held; the said socket is provided at its lower end with the driving pin 28 which slides in the groove 30 of the shifting tube. Approximately in the upper third of the socket is a circular indentation 33 which holds the lip-stick fast.

The closing flap 7 shown in Figures 6 and 7 is curved in order to slide under the curved plane of the opening 12 and ends in its upper part in a half circumference 7' perfectly fitting the half-cylindrical surface of the case. Its base is provided with a hinge 34 which substantially extends along a quarter of the length of the said base and lies immediately on the left of the axis. The hinge 34 is pivotally connected with the corresponding hinge 35 which is also rolled up and is part of another piece 36 forming a link comprising a hook 37, a guide 38 and a spring 39 terminating in an end part shaped correspond-

ingly to the curvilinear part 22 of the guiding bridge 3.

In order to use the case, one pulls out the base 5 (Figure 8), turns it to the right (Figure 9) and drives it back (Figure 10). For driving the lip-stick in again one performs the same movements but in a reverse direction, that is to say, one pulls out the base, turns it to the left, and drives it back again.

10 The working will be explained particularly with reference to Figures 11, and 17 to 21.

The case being closed, the hook 37 of the link 36 is held under the pressure of the spring 39 in the hole 40, resulting from the cutting out of 15 the buffer 24 (see Figure 17). When the base 5, fast with the shifting tube 4, is pulled out, the lower edge of the sloping face 32 on the tube 4 pulls the link 36 downwardly through the medium of its hook 37, which drives the flap 7 back, the flap sliding clear of the opening 12 of the cover 1.

20 When the flap 7 is almost at the end of its stroke, and when the opening in the cover is completely unobstructed, the guide 38 of the link 25 36 rises along the small slope 18 of the slide 2. At the end of its stroke the hook 37, fast with the guide 38, has been raised sufficiently by the slope 18 for the lower edge of the slope 32 on the tube 4 to pass below the hook 37 and move further until the buffer 24 comes into contact with the bottom 5' of the case 1. In this latter position the end of the spring 39 of the link 36 is positioned behind the bent part 22 of the guiding bridge 3 and prevents the flap 7 falling down 30 under the action of its own weight during the outward movement of the lip-stick.

35 When the base 5 and the shifting tube 4 are turned from the left to the right (see Figure 11), the buffer 24, which during its downward movement towards the bottom 5' of the case 1 has moved along the left side of the web 23 of the guiding bridge 3, passes to the right of the web 23 and can thus rise again along the said web but this time on the right of the web. During 40 the left to right turning of the tube 4 the pin 28 of the stick holder socket 6 moves out of the small groove 27 and to a position in front of the clearance 29 and is thus able to rise freely again when the base 5 is driven back. The parts 45 will then be in the positions shown in Figure 20, the pin 28 being caught in the small right angle groove 31 of the slide 30 of the shifting tube 4, whereby the pins 28 and sockets 6 are locked onto the shifting tube 4.

50 55 When the base 5 and the tube 4 are driven back in the third step of the movement as shown in Figures 10 and 21, the stick-holder socket 6, which is locked onto the tube 4 by its pin 28, rises with the tube 4 and causes the lip-stick to project out 60 of the opening 12.

In the course of this movement the buffer 24 occupies the position shown in Figure 21 and in dotted lines at 24' in Figure 11, and rises along the right side of the web 23 of the guiding bridge 65 3. Furthermore, the pin 28 moves into the position indicated in dotted lines at 28' in Figure 11, and glides along the right leg 15 of the slide 2 which works as a brake. Consequently the stick-holder socket 6 cannot become disconnected from the shifting tube 4 and cause a wrong movement.

In order to drive the lip-stick back into the cover 1, one pulls the base 5 and the tube 4 back to the position shown in Figures 9 and 20. The pin 28 again passes along the clearance 29 and 75 comes to lie in front of the small groove 27.

5

Then the tube 4 is turned back from right to left (counter-clockwise as viewed in Figures 11 and 20), thus moving the pin 28 out of the transverse part 31 of the slide 30, and into the groove 27 in the bridge 3. The buffer 24 passes from the right to the left of the web 23 of the guiding bridge 3 and is ready for raising again. The parts will then be in the positions shown in Figure 8.

On driving the shifting tube 4 to the position shown in Figures 1 and 19, the buffer 24 on the shifting tube strikes against the hook 31 on the link 36 and pushes it back. The guide 38 on the link 36 moves down along the slope 18 on the stirrup 2, and the hook 31 falls back into the hole 40 on the shifting tube 4, thus coupling the link 36 and the flap 1 with the shifting tube 4. Then the buffer drives the link 36 and flap 1 further till the opening 12 is completely closed by the flap 1, and the tube 4 is locked by its notch 21 engaging the elastic part 20 of the slide 2.

What I claim is:

1. In a lip-stick case, a cover having at one end an opening for the passage of the stick; a tube mounted to slide to an inner position within said cover and to an outer position in which it projects partially out of the other end of the cover; a stick-holding socket mounted to rotate and to slide in said tube; first and second parts fixed with respect to said cover and said socket respectively and being mutually interengageable by rotation of said socket in one direction relatively to said cover for latching said socket in retracted position in said cover; and means on said tube operable upon rotation of said tube when in its outer position for rotating said socket together with said tube in a direction opposite to said one direction to disengage said parts and for operatively coupling said tube to said socket for longitudinal driving of said socket by said tube, whereby subsequent longitudinal movement of said tube to its inner position will drive said socket and project the stick through said opening.

2. In a lip-stick case; a cover having at one end an opening for the passage of the stick; a tube mounted to slide to an inner position within said cover and to an outer position in which it projects partially out of the other end of the cover; a stick-holding socket mounted to rotate and to slide in said tube; a longitudinally extending slot in said tube having a transversely extending coupling portion; a pin on said socket projecting through said slot; and a part within and fixed with respect to said cover and being formed with a transverse latching slot adapted to receive said pin for latching said socket in retracted position in said cover, said tube being rotatable in one direction when in outer position for engaging said coupling slot with said pin to couple said tube and said socket for longitudinal driving and for disengaging said pin from said latching slot, and said tube being rotatable in the opposite direction when in its outer position for uncoupling said pin from said coupling slot and for moving said pin into said latching slot to lock said socket in retracted position in said cover.

3. In a lip-stick case, a cover having an arcuate end and an opening therein for the passage of the stick; a movable arcuate flap for closing said opening; means mounting said flap to slide to closed position in which it extends across said opening and to open position within said cover and clear of said opening; a member mounted to

6

move longitudinally to an inner position in said cover and to an outer position in which it projects beyond the end of the cover opposite said arcuate end; disengageable connecting means on said member and said flap engaged with each other when said member is in its inner position and being operable to move said flap to its open position when said member is being moved to its outer position; means for disengaging said connecting means when said member is moved to its outer position; a stick-holder; and means for coupling said member, when in its outer position, to said stick-holder to enable the lip-stick to be projected through said opening by return movement of said member to its inner position.

4. Construction as defined in claim 3 in which said longitudinally movable member is mounted to rotate about its longitudinal axis for coupling it to said stick-holder.

5. Construction as defined in claim 3 and including spring means for yieldably holding said flap in its open position when said longitudinally movable member is being moved to its inner position for projecting the lip-stick through said opening.

6. A lip-stick case, comprising a cover provided with a front rectangular face, a rear semi-cylindrical face, and two parallel faces connecting the semi-cylindrical face with the rectangular face, the rectangular face being extended in its head portion as a quadrantal cylindrical face, the generatrix of which is at right angles to the side faces of the cover, said quadrantal cylindrical face being provided with a generally circular aperture, a slide and a bridge rigidly mounted within the cover and together providing a guide, a tube slidably and rotatably mounted by said guide and said cover to move between an inner position to an outer position in which it projects through and beyond the end of said cover opposite said aperture, a longitudinal groove in said tube having a transverse end portion, a lip-stick socket slidable and rotatable in said tube, and a pin secured to said socket and projecting into said groove, said tube being rotatable when in its outer position for moving said groove transverse end portion to embrace said pin, said tube being then movable longitudinally inwardly from its outer position for pushing said socket toward said aperture to project a lip-stick carried by said socket through said aperture.

7. A lip-stick case according to claim 6, wherein a clearance or gap is left between the top edge of the slide and the quadrantal-cylindrical face of said cover, in which gap a flap for closing said aperture is slidable between open and closed positions, the size of said gap being defined by a projection provided on the edge of the slide, which projection abuts against the quadrantal-cylindrical face.

8. A lip-stick case according to claim 6, wherein the slide has the form of an arcuate stirrup having two legs notched or dented to enable said slide to receive the bridge, one of these legs being bent over inwardly and forming a cylindrically curved flange hugging the cylindrical surface of the tube.

9. A lip-stick case according to claim 6, wherein the slide has the form of an arcuate stirrup having two legs notched or dented to enable said slide to receive the bridge, one of these legs being bent over inwardly and forming a cylindrically curved flange hugging the cylindrical surface of the tube, the top end of the flange being separated from the leg by a narrow slit

to form a resilient lug, a notch being provided in the tube to be engaged by said lug, thus locking the tube from sliding out of the cover.

10. A lip-stick case according to claim 6, wherein in the bridge is of T shape having a web and flanges, and the slide has the form of an arcuate stirrup having two legs notched or dented to enable said slide to receive the T shaped bridge, the flanges of said bridge resting in the notches of the slide, one of these flanges, resting on the edge of one of the legs being bent over inwardly and being provided with a depression; the T-web serving as a guide for a buffer provided on the tube for engaging a part of said cover to prevent complete withdrawal of the tube from the cover, said buffer being capable of sliding on either side of the T-web and to move from one to the other side of said T-web when the tube is turned due to the fact that a step is provided on the bottom or rear end of said T-web; the lower end of the other flange on the bridge, which rests on the other leg of the slide being provided with an extension bent inwardly to form a support on the tube, said support being provided with a groove for engaging the pin of the socket, the clearance separated from the supporting face by the groove being bent up so as to enable the pin to slide past same when the tube is turned.

11. A lip-stick case as defined in claim 6, wherein in a flap for closing said aperture is bent in the form of a cylinder quadrant to hug the corresponding face of the cover, the top end of said

flap being conformed to the quadrantal cylindrical face of the cover, and the bottom or rear end of the flap being provided with a hinge extending over a quarter of its length and laterally offset from the center line of the flap, said hinge providing a connection between the flap and a swinging structure comprising a hinge member, a hook, a guide, and a leaf spring for moving said flap selectively to open and closed positions with respect to said aperture.

12. A lip-stick case as defined in claim 6, wherein in the bridge is of T shape having a web and flanges and a portion of one flange of the T-shaped bridge is bent and cooperates with the end of a leaf spring secured by a hinge connection with a flap bent in the form of a cylinder quadrant to hug the corresponding face of the cover, said flap being movable to open or close the aperture in said cover.

20 SOPHIE FRYDLENDER.
